UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-FINISHING MACHINE.

1,080,341.

Specification of Letters Patent.

Patented Dec. 2, 1913.

Application filed January 24, 1910. Serial No. 539,756.

To all whom it may concern:

Be it known that I, GEORGE S. HILL, a citizen of the United States, of Strafford, in the County of Strafford and State of New Hampshire, have invented certain new and useful Improvements in Buttonhole-Finishing Machines, of which the following is a specification.

This invention has relation to that class 10 of machines which may be used for finishing buttonholes, and by which the thrum ends and the stay cord are gathered in line and are stitched to the under face of the work between the ends of the buttonholes by blind 15 stitches.

The principal object of the invention is to provide certain improvements in machines of the general character referred to, in consequence of which such machines may be 20 run at a higher speed than heretofore possible, so as to increase the production or output of such machines, and thereby decrease proportionately the cost of manufacture of button shoes and gaiters.

25 A further object of the invention is to eliminate what has heretofore been regarded as an essential feature of construction in such machines, to wit; the gooseneck, and to provide the machines with a substantially 30 flat top, so that the work may be presented with the greatest possible ease to the operating elements or instrumentalities of the machine. By so doing I also provide for operating the work bender directly by the 35 driving shaft located below the work support, and thus obviate lost motion.

A further object of the invention is to bring together into a single organized machine, a stitch-forming mechanism, wherein 40 the needle is positively reciprocated in the line of feed beneath the work support, a bender, for bending the material into the path of the needle, which is located above the work support and is positively moved 45 toward the material by connections with the driving shaft beneath the work support, a feeding mechanism which engages the material at one side of the bender and is positively moved into engagement with the material 50 as the bender is raised, and moved away from the material as the bender is lowered, and a presser foot which may engage the material at one side of the bender and co-operate with the feeding mechanism. 55 It should be understood that while the ma-

chine as illustrated and as preferably constructed comprises all of these elements in combination, my invention also includes various other combinations of more or less of these and other elements, as set forth in the 60 claims.

Another object of the invention is to locate all the power transmitting elements for the operating instrumentalities within the machine case, whereby these parts are not 65 only effectively housed from dust, dirt and lint, but the upper face of the work support is substantially free from projecting parts, which facilitates the handling of the material during the stitching operation, as has 70 been above suggested.

A still further object of the invention is to eliminate, so far as possible, spring-tensioned cam-actuated levers and to utilize in lieu thereof eccentrics and cranks or other 75 direct connections so that the operating instrumentalities may be actuated smoothly at a high rate of speed.

In carrying out these and other various objects, I have made a number of improvements which I have illustrated in the accompanying drawings and will describe in detail in the following specification and point out in the appended claims.

Referring to the accompanying drawings, 85 which show by way of illustration one embodiment of the invention,—Figure 1 represents in plan view a machine embodying the invention; in this figure, the work support is broken away to illustrate the mechanism 90 contained in the case; Fig. 2 represents a section on the line 2—2 of Fig. 1; Fig. 3 represents a left end elevation of the machine partially in section; Fig. 4 represents a transverse section through the machine on 95 the line 4—4 of Fig. 2; Fig. 5 represents a similar section on the line 5—5 of Fig. 1, looking in the direction of the arrow; Fig. 6 represents a similar section through the machine on the line 6—6 of Fig. 1, looking 100 in the direction of the arrow; Fig. 7 is a detail view illustrating the double three-cornered eccentric, and a portion of the bender lever which is operated thereby; Fig. 8 represents a transverse section on the line 105 8—8 of Fig. 1; Fig. 9 represents a longitudinal section on the line 9—9 of Fig. 1; Figs. 10 and 11 represent in detail the means for mounting the bender and for adjusting the same in the direction of its length; Fig. 110

12 represents in plan view that portion of the work support which has the throat plate, the cover plate for the shuttle plate being removed; Fig. 13 represents a section on the line 13—13 of Fig. 12; Fig. 14 represents a longitudinal section through a portion of the work support to illustrate the yielding work-receiving jaws between which the work is forced by the bender; Fig. 15 represents a front elevation of the machine and illustrates in detail the spindle for the thread cone, the presser foot and the bender-supporting lever being in section; Fig. 16 illustrates the finished work; Figs. 17 and 18 illustrate the connections between the main driving shaft, the needle bar and the looper; Fig. 19 illustrates the double eccentric by which the bender is actuated; and Figs. 20 to 22 inclusive, illustrate a different form 20 of mechanism for laterally shifting the needle.

The machine, which is illustrated upon the drawings and which I shall now proceed to describe, is designed to have the needle penetrate the work in a direction opposite to the direction of feed and generally parallel with the thrum ends and stay cord, as they extend between two adjacent buttonholes, which needle is also moved laterally relative to the material, after each engagement therewith, so as to enter the material first on one side and then on the other side of the thrum ends and stay cord, and thus to lay the threads between successive stitches across said thrum ends and stay cord, in the manner shown in Fig. 16.

The work, prior to each penetration by the needle, is forced downwardly by a bender, so as to be slightly bent in order that the needle may pass through the convex portion thereof and emerge therefrom and form a loop in the needle thread in position to receive the shuttle carrying the shuttle thread. After the needle is withdrawn from the work, the work is advanced one step by the feeding mechanism, the needle is moved laterally to the other side of the thrum ends and the stay cord, and the bender again forms a new bend in the work, so that the needle may again penetrate it, and form a second loop in the needle thread to receive the shuttle.

In addition to the stitch-forming mechanism, the bender for bending the material into the path of the needle and the feeding mechanism above referred to, the machine comprises generally a hollow case, consisting of a lower portion or base and a swinging upper portion or work support, having meeting side and end walls. Within the case are contained all of the instrumentalities of the machine, with the exception of the bender and a portion of its supporting lever, the presser foot and the presser foot lever.

65 The bender-supporting lever is journaled

on a shaft located within a shallow raised portion on the top of the work support; otherwise the work support is flat, so that the work may be shifted about and presented with the greatest ease to the operating instrumentalities of the machine. The work support is hinged to the base and carries or supports all of the operating portions of the machine, including the driving belt pulley on the main driving shaft, so that when the work support is raised, the said instrumentalities are all exposed to view and are accessible for adjustment, oiling or repair. The loose pulley for the driving belt is located within the case, and is mounted on a stud shaft supported in the interior of the base in such position that, when the work support is lowered to its normal position, it is in axial alinement with the main driving shaft, and the fast pulley thereon, so that the belt may be easily shifted from the fast pulley to the loose pulley or vice versa. I provide mechanism for stopping the rotation of the main driving shaft and automatically shifting the belt from the fast pulley to the loose pulley, and I also provide mechanism for locking the belt shifter against movement when the work support is raised, this locking mechanism being moved to inactive position automatically when the work support is lowered to its normal horizontal position. However, it will be understood, of course, that some of these mechanisms, and especially the locking mechanism, may be omitted or modified, if desired, without affecting other features of the invention, or the essential operation of the machine.

Proceeding to a more detailed description of the machine which is shown in the accompanying drawings to illustrate one embodiment of the invention, the case comprises a hollow base 20 and a hollow work support 21, which are hinged together by suitable hinges 22, at the rear of the case, and which have meeting end and side walls. In plan view, the case is generally oblong with a forwardly projecting portion at its left end. The work support is provided with dowels 23 at its front corners which project into complementary apertures in the corners of the base when the work support is in its normal position, as shown in Fig. 15. The base is provided at the front and to the right of the forward projecting portion with a shallow receptacle 24 having pockets 25 and 26 for small tools and needles respectively, and with pockets 27 to receive filled bobbins. As illustrated, this receptacle is closed by a hinged cover 28, which when raised or swung about its hinge, automatically lifts the cover for the shuttle, as will be subsequently explained, so as to expose the shuttle and permit the removal of the empty bobbin.

The main driving shaft 29 is journaled in bearings 30, 31, which depend from the under side of the work support, as best shown in Figs. 1 and 2. On the right end of the shaft 29 is a fast belt pulley 32. Loosely mounted on a stud shaft 33 is the loose pulley 34. The stud shaft 33 is rigidly secured in a boss on the inner face of the end wall of the base, and it is in axial alinement with the shaft 29 when the work support is closed or horizontal, so that the two pulleys 32 and 34 will be located in close proximity side by side, or in confronting position, as shown in Fig. 2, in consequence of which the belt 35 may be easily shifted from one of said pulleys to the other.

The belt-shifting mechanism comprises a belt shifter, consisting of a looped rod or wire 36, shown in dotted lines in Fig. 2, so as to embrace one of the stretches of the driving belt, the end of said rod or wire being bent at right angles to the loop, and being affixed in an arm 37 secured on a hub 38 rigidly attached to a horizontally arranged rock shaft 39, whose ends are journaled on pointed screws 40, 40, passed through the front and rear walls of the base, as shown in Fig. 4. The screws are locked after adjustment by lock nuts 41. The arm 37 has an extension 42 with an apertured head 43, through which is passed a rod 44 to a treadle (not shown) beneath the table on which the machine is supported, the base of the machine being apertured to permit the passage of said rod. The rod is provided with a spherical head 45, as shown in Fig. 9. By drawing down the rod 44, the shaft 39 may be rocked to swing the belt shifter 36 in such position as to shift the belt 35 from the loose pulley 34 to the fast pulley 32. A spring, which will be subsequently explained, rocks the shaft 39 in the opposite direction when the rod 44 is released by removing the foot from the treadle.

In order to lock the belt shifter in the position which it occupies after shifting the belt to the loose pulley, during the time when the work support is raised or swung about its hinges, I may provide a latch 50 which is illustrated in Fig. 4. Said latch consists of an arm 46 which at its lower end is provided with trunnions 47 resting in sockets in the bottom of the base. A spring 48 is attached to the latch and to the rear wall of the base, so as to hold the free end of the latch, when the work support is in its horizontal position, against a cam projection 49 depending from the under side of the bed.

The latch is provided with a shoulder or projection 50, which when the work support is raised, and the free end of the latch is released by the cam projection 49, projects under the head 43 of the belt-shifting lever 42, and holds said lever in its raised position, and prevents its being depressed by the treadle (so as to throw the belt off from the loose pulley), and the belt-shifting lever will be thus locked so long as the work support is raised. When the work support is closed or swung downwardly, the cam projection 49 on the bed engages the free end of the latch and moves it into an inactive position to release the belt-shifting lever. In lieu of the particular locking mechanism herein described, any other form may be employed, or it may be wholly omitted as already suggested, without interfering with the general operation of the machine. The rock shaft 39 also serves to move the stop-motion devices into and out of active position, the stop-motion devices being supported by the work support. Of course, it will be understood that any suitable stopping device may be utilized, although the one which I have illustrated and shall now describe, is well adapted for the purpose.

Mounted loosely on the shaft 29 is a notched stop cam 52, into the notch 53 of which may project the beveled end of a stop pin 54 clamped in the split end of an arm 55 (see Fig. 4) having a hub 56 secured upon a shaft 57 journaled at its rear end in a bearing 58 and at its forward end in a hollow screw 59. A spring 60 is interposed between the ends of the screw and the hub 56, the tension of the spring being varied by means of the screw 59. The shaft 57 is adapted to rock and also slide longitudinally.

On the rock shaft 39, which I have previously described, there is mounted a forked lever 61, which embraces the stop pin 54, and, when the shaft 39 is rocked about its axis, the arm 55 with the stop pin 54 is rocked thereby about the axis of the shaft 57, so as to move the end of the stop pin into and out of alinement with the cam 52. I have stated that the cam is loose upon the shaft 29, and consequently in order that it may rotate with the shaft, it is provided with a pin which projects through a curved slot in the fast belt pulley, and bears against a spring located in the socket in said pulley. I have not illustrated in detail the said pin, slot and spring, as they are well known constructions, the spring serving as heretofore to minimize the shock due to the sudden stopping of the cam.

Pivoted to the forward end of the stop pin there is a rod 62, which extends longitudinally of the work support, and is connected to the upwardly projecting arm 63 of a bell crank lever, which is pivoted to the rear side of a post 64. The said post projects upwardly into a socket 65 formed on the under side of the work support, and is adjustably secured in place by a set screw 66. The rod 62 extends through a bracket 67 attached to the post, as shown in Fig. 2,

and between the bracket 67 and a collar 68 fastened on the rod 62 there is interposed a spring 69 which exerts its tension against the rod in such manner as to normally hold 5 the stop pin 54 in alinement with the notched cam, and to hold the belt shifter in alinement with the loose pulley. This is the spring to which I previously referred as the means for moving the belt shifter so as to 10 shift the belt to the loose pulley when the treadle is released by the operator.

Again, referring to the bell crank to which the rod 62 is connected, it will be seen by examining Fig. 2, that it is provided with 15 a substantially horizontally arranged arm 70, which, as will be explained, is utilized to raise the presser foot so that, when the belt is shifted and the main driving shaft is stopped in its rotation, the machine comes 20 to a state of rest with the presser foot raised.

I desire to point out that by reason of the arrangement which I have described, the fast and loose pulleys are arranged within 25 the case where they are completely covered and protected, and hence the work is prevented from coming into engagement with the rotating parts. To keep the work from striking against the belt, the rear portion 30 of the base is provided with a rearward extension 71, which forms a casing therefor, (see Fig. 4).

The material to be stitched is placed on the work support with the thrum ends and 35 stay cord against the work support and extending in the general direction of the feed.

The stitch-forming mechanism as in this general type of machine is located and operated wholly beneath the work support. As 40 herein shown, said stitch-forming mechanism comprises an eye-pointed needle, which is arranged in a plane parallel with the face of the work support and parallel with the line of feed of the work, or, in other words, 45 the needle is arranged in a line transverse to the longitudinal lines of the machine and of the main driving shaft, whereby the needle is caused to move in a direction parallel with the thrum ends and stay cord.

The needle-operating mechanism may be 50 formed in a variety of ways. As shown in Figs. 8, 13 and 14, the needle 101 is clamped in a needle carrier 102. The lower end of the needle carrier is secured to a horizontally arranged needle bar 103 which is located 55 below the work support and extends from front to rear thereof. The needle projects from its carrier toward the front of the machine, and in a direction opposite to the line of feed of the work. The needle bar is mounted to reciprocate in a support 60 65 104, which is pivoted at its rear end to move about a vertical axis.

It will be seen that, as shown in Fig. 8, 65 the rear end of the swinging support is pro-

vided with a hub 105, through which a headed pin or pivot 106 is passed upwardly into a boss on the under side of the work support. The hub 105 is out of alinement with the needle bar 103, so as not to interfere with its reciprocation. The forward end of the support has a transverse slot 205 to receive a thin guide member 204 on a pin 201 projecting laterally from a depending bracket 202, said pin being secured by a 75 screw 203.

The needle bar and the swinging support are elongated sufficiently so that, when the support is moved about its axis to swing the needle laterally, first to one side and then 80 to the other side of the thrum ends and the stay cord, the stitches on the two sides will be substantially parallel. The support is oscillated about its axis by means of the carrying mechanism actuated by the main driving shaft.

Secured upon the main driving shaft 29 is a spiral gear 107 (see Fig. 2), which intermeshes with and drives a larger gear 108, the ratio of the gears being as one to two. 90 The gear 108 is fast upon a vertical shaft 109, which projects downwardly through a vertical bearing afforded by the work support, as indicated at 110.

On the lower end of the shaft there is a 95 crank pin 111, to which is pivoted a pitman 112, extending longitudinally of the machine, and having at its left end a fork which is pivoted to a projection 113 extending laterally from the free end of the swinging support 104. According to this arrangement, the swinging support for the needle bar is moved in one direction and then in the opposite direction, once for each 100 two complete rotations of the main driving shaft, in consequence of which the needle is caused to take a stitch first on one side of the thrum ends and the stay cord and then on the other side of the same, as previously 105 explained.

In Figs. 20 to 22 inclusive, I have illustrated a different form of mechanism for moving the needle laterally which is believed to be simpler and more satisfactory than the corresponding mechanism hereinbefore described. In lieu of mounting the needle bar upon a support which is pivoted to swing about a vertical axis, as hereinbefore described, it is caused to traverse an unvarying path, and the needle carrier is arranged to swing laterally about the axis of the needle bar. The needle bar 103 is arranged to slide in guides 180, and 181. Of the two guides, the latter 181, is in the form of a two-armed or V-shaped bracket, depending from the work support to which it is attached. The needle carrier 182 has in its side a bracket which is apertured to receive a guide pin 183, which projects forwardly from a connecting rod or pitman 110 115 120 125 130

184. This connecting rod is made in two sections, connected by a threaded coupling 185, so that the rod may be elongated or contracted as described.

- 5 A portion of the connecting rod or pitman is passed between two guides 186 depending from the work support to hold it against movement in lines parallel with the path of movement of the needle bar. The end of 10 the connecting rod is connected to a crank pin or eccentric 187 on the end of a shaft 188, which is journaled below the work support, and which carries a spiral gear 189 intermeshing with and driven by a complementary gear 190 on the main driving shaft 29. As the connecting rod 184 is vibrated longitudinally, the needle carrier will be 15 swung about the axis of the needle bar by reason of the sliding engagement of said 20 needle carrier with the guide pin 183 on the said connecting rod or pitman. I utilize this rocking motion of the needle carrier to slightly advance and retract the needle longitudinally with reference to the needle bar, 25 so as to compensate at least to some extent, for variations in the relationship of the needle and the shuttle, due to the lateral movement of the needle. In other words, when the needle is on one side of the thrum 30 ends, it is projected farther with reference to the hook of the shuttle than when it is on the other side of said thrum ends. This compensation is accomplished by forming a coarse thread 191 on the end of the needle 35 bar and forming an internal complementary thread in the needle carrier. The needle carrier is split, as shown in Fig. 22, and an adjusting screw 192 is used to draw the split portions of the nut on the needle carrier 40 against the threaded portion of the needle bar. The ratio of the gears 190 and 189 is as one to two, just as in the case of the gears 107 and 108, previously referred to.

Any convenient mechanism may be utilized for reciprocating the needle bar, although I find the mechanism which I shall now describe to be satisfactory for the purpose.

Secured to the left end of the main driving shaft 29 next to the double eccentric 85, previously described, is a disk or crank arm 114, which is provided with a crank pin 115. This crank pin is provided at its end with a second crank arm 116, on the end of which 55 is another crank pin 117. The last mentioned crank pin has at its end a third crank arm 118, on which there is still another crank pin 119, for a purpose to be described. Connected to the crank pin 117 is a pitman 60 or connecting rod 120 which, at its forward end, is pivoted to a pin 121 projecting laterally from a block 122, affixed to the needle bar by a set screw or other convenient means. The swinging support for the needle bar 65 is slotted, as shown in Fig. 3, and the block

122 occupies the said slot and reciprocates longitudinally thereof as the needle bar is actuated by the rotation of the crank pin 116. In the construction shown in Figs. 20 to 22, the block reciprocates between the 70 guides or brackets 180, 181.

From the above description it will be noted that the crank pin 115 is disposed on the opposite side of the center of the shaft 29 from the crank pin 117. By this arrangement of the crank pins, the parts connected with the shuttle move in opposition to the parts connected with the needle, and, therefore, vibration in the shaft 29 is reduced to a minimum as the momentum of the parts moving in one direction is substantially counterbalanced by the momentum of the other parts moving in the opposite direction.

The take-up is illustrated at 123. It consists of a bent arm, as shown, having an eye 124, through which the thread passes. Midway between its ends, the take-up lever is connected by a pivot 125 to an arm 126 which is fulcrumed upon a pivot 127 journaled in a bracket 128 secured to and depending from the under side of the work support. At its forward end, the take-up lever is pivoted upon the crank pin 119, which, it will be remembered, is carried on the crank arm 118 affixed to the crank pin 117 on the crank arm 116. This construction of the take-up lever and the link connections for actuating it and their mode of operation are not novel in themselves, but only as to their arrangements 100 in relation to the other elements, and more especially the work support, the needle and needle bar. The take-up arm is pivoted at its lower end, and its free end which engages the needle thread, swings in an arc 105 which lies substantially in a line containing the path of movement of the needle. By this arrangement of the take-up arm, the pull of the needle thread in setting the stitch is in line with the needle, which avoids any lateral strain on the needle which might spring the same. Furthermore, the pull of the take-up arm is in line with the feed, which also tends to hold the material in its proper line of travel, whereby the needle may enter the material entirely at one side of the thrum ends, and then entirely at the other side thereof, so that all of the thrum ends may be covered by the stitching threads. The connection between the take-up arm and 115 the driving shaft causes said take-up arm or lever to move slowly forward as the needle bar is moved forward to carry the needle through the work, and to be withdrawn rapidly, when the needle bar is retracted, to 120 take up the loose thread.

The needle thread is drawn as usual from a thread cone 129, as shown in Fig. 15, and it passes from the cone through a thread guide 130, consisting of coiled wire attached 125 130

to the raised projection on the work support. From the thread guide 130, the thread passes around a spring-tensioned thread check 131, thence through the spring tension 132 (see 5 Fig. 1) and downward through an aperture 133 (see Fig. 3) through a thread guide 134 attached to the under side of the work support. Thence the thread passes to the eye 124 of the take-up, and then to the eye of 10 the needle.

Coöperating with the needle to form the stitch, is an oscillatory shuttle, which is indicated as a whole at 135. There is no novelty in the shuttle itself, it being of a well 15 known commercial type, so that it will not be described in detail. It is located horizontally below the work support, as shown in Fig. 8, and is caused to oscillate through an arc of more than 180 degrees. The shuttle 20 carrier consists of a vertically arranged shaft 136 having a shuttle driver of the well known construction, the machine being provided with the usual shuttle-race. The shuttle carrier 136 is journaled in a bearing 137 25 formed on a bracket depending from the work support, as shown in Fig. 8, and on its lower end it is provided with an arm 138 having a crank pin 139. The crank pin 139 extends into the fork end of an arm 30 140, as shown in dotted lines in Fig. 1. This last mentioned arm is secured upon the lower end of a shaft 141, mounted in a bearing in the same bracket which affords a bearing for the shaft 136. The two shafts 35 136 and 141 are parallel. At the upper end of the shaft 141 there is an arm 142 which is connected by a pitman 143 with the crank pin 115 on the disk 114. The crank pin 115 is rounded to fit in a complementary aperture 40 in the pitman 143. The pitman 143 is formed in two parts, having a threaded connection, so as to be longitudinally adjustable. Through the medium of the crank pin 115, and the pitman 143, the shaft 141 is 45 rocked through an arc of substantially 90 degrees, and, by reason of the pin and slot connection between the arm 138 on the shaft 136 and the arm 140 on the shaft 141, the shuttle-carrying shaft 136 is oscillated 50 through an arc of more than 180 degrees during each rotation of the main driving shaft.

In order that the material may be bent into the path of the needle, I have formed 55 the work support with an aperture in which is seated the throat plate 86. Said throat plate is provided with a groove 87, which extends longitudinally of the machine and transverse of the line of feed. In the bottom 60 of the groove 87 is a slot 88, which allows the material resting on the work support and throat plate, to be bent downward into the path of the needle, which, as above noted, reciprocates close to the under face of 65 the work support.

As a means for bending the material into the groove in the throat plate and through the slot into the needle path, I have provided a bender 72, which is located above the work support with its lower beveled end 70 directly above said slot. The bender 72 is mounted on an arm or carrier 73, arranged generally transversely of the longitudinal lines of the machine, its forward end being curved to the left, as shown in Fig. 1. The 75 said arm has an elongated hub journaled upon a shaft 74, the ends of which are mounted in the sides of a raised or hump-like projection 75 of the work support. The lever extends through an aperture in the 80 wall of the projection, its rear and lower end projecting downwardly into the case, as best shown in Fig. 6. The forward end of the arm or bender-supporting lever is split, as shown in Figs. 10 and 11, and is 85 apertured to receive the bender 72. The bender is slotted to receive a key 76, which is held in place by the clamping screw 77 for the split portion of the lever, whereby the bender is held against rotation. The 90 bender is internally threaded to receive the reduced end 78 of a screw having an enlarged portion 79, which is threaded into the lever. The two portions 78, 79, of the screw are oppositely threaded, and hence, 95 by rotating the milled head 80, the bender may be adjusted longitudinally up and down without the possibility of lost motion. The lower end of the bender is beveled and slightly rounded, as indicated at 810, to engage the work and bend it between work-receiving jaws, which will be hereinafter described.

The lower portion of the lever 73 which extends into the case is forked, the arms 105 being indicated at 81 and 82 respectively. The lever is slotted also as indicated at 83, and a clamping screw 84 is passed through the split portions, so as to adjust the arms 81, 82, relatively to each other. The arms 110 81 and 82 are staggered, so that they are out of alignment with each other, and they engage separate peripheral portions of a double eccentric or cam on the main shaft 29. The eccentric is indicated as a whole 115 at 85 in Fig. 19, and it consists of the two members *a* and *b*. The member *a* is engaged by the fork arm 81, whereas the member *b* is engaged by the fork arm 82, see Fig. 7. These two members may be made separately, although preferably they are formed in one piece. It will be observed that the member *a* has a radially extended bearing surface *a'*, concentric with the shaft 29, of approximately 150 degrees more or less, so 120 that, when the bender is forced downwardly it will dwell at its lowermost position for a sufficient time to enable the needle to penetrate the work, form a stitch by reason of the co-action of the shuttle, and then recede 125 130

or nearly recede from the work before the bender is again raised. The member b has a radially contracted portion b' of substantially the same number of degrees and a radially extended portion b^2 which operates to raise the bender when it engages the yoke arm 82. These two members of the eccentric are so formed that they always engage their respective fork arms and prevent any lost motion between the lever and the eccentric. The fork arms may be drawn together by the clamping screw 84 in the event that the parts become worn. The action of the eccentric upon the bender-supporting lever is, as stated, to depress the bender and thereby force a portion of the work into the path of the needle and hold the work temporarily until the stitch is formed, and then to move the bender away from the work, so as to permit the feeding thereof. The bender remains elevated until the feed has been accomplished, and is then depressed again.

The projection on the work support is arranged in rear of and at one side of the bender, so as to allow a free feeding of the material being stitched. The lever 73 is laterally deflected after leaving the slot in the raised projection, so as to properly carry and support the bender.

By providing the pivoted bender carrier, I am able to dispense with the goose neck which heretofore has been considered an indispensable part of machines of this character. Another advantage in using the pivoted bender carrier is that I am able to actuate the carrier directly and positively by instrumentalities on the main driving shaft, and thus eliminate a number of parts and provide against lost motion.

I sometimes find it desirable to provide jaws into which the material may be forced by the bender, which jaws hold the material for the entrance of the needle. In the drawing I have shown two work-engaging jaws 91, 91. These jaws are pivoted on a stud 90 carried by the bracket 89, secured to the under side of the work support. The jaws are located a little to one side of the middle of the slot and beyond the end thereof, as shown in Figs. 13 and 14. The jaws are flared upwardly and outwardly, so as to readily receive the material between them as the bender carries it down through the slot in the throat plate. Engaged with these two jaws are the ends of a curved or C-shaped leaf spring 92, which tends to force them together, but the extent to which the jaws may be moved toward each other is limited by a pointed adjusting screw 93 which enters the space between said jaws, as indicated in Fig. 13, said screw being passed through the bracket 89. The free ends of the jaws are provided with apertures 94, through which the needle may pass

in penetrating and receding from the work. It will be observed that the jaws are pivoted upon an axis parallel with the surface of the work, and they are spring-pressed so that they cause the bent portion of the work closely to hug the beveled end of the bender, and thus to be bent comparatively sharply about the end of the bender, and thus present the work accurately to the needle. By placing the jaws under spring pressure and permitting them to yield, they accommodate themselves to work of varying thicknesses.

The pivot for the jaws is, as previously stated, a little to the rear of the slot in the work plate, and the jaws are slightly inclined rearwardly and downwardly from the vertical, whereas the bender is mounted upon a swinging arm whose pivot is still farther to the rear of the work plate and also above the plane of the main portion of the work support. The effect of this construction and arrangement is to prevent the work from dragging backward in a direction opposite to the line of feed, while being depressed by the bender.

So far as I am aware, I am the first to have provided yielding or spring-pressed work-engaging jaws in a machine of this type. Such jaws insure that the work will be presented accurately to the needle, as above suggested, but it is contemplated that, especially on relatively thin or flexible materials, the jaws may be omitted without seriously impairing the successful operation of the machine.

For carrying the material through the machine step by step between the formation of successive stitches, I have provided a feeding mechanism which is likewise operated directly from the main driving shaft, and, as herein shown, is of the four-motion type. Briefly described, it consists of a feed dog 144, which is secured to a feed bar 145 (see Figs. 8 and 12). Said bar has a lateral extension at its rear end, as shown in Fig. 110, 9, which is pivoted upon pointed screws 146 projecting toward each other from arms 147, formed on a rock shaft or bar 148 in turn pivoted upon pointed screws 149, passed through ears depending from the work support at the rear thereof. The rock shaft or rock bar 148 has clamped thereon a lever 150, which has a forked end (see Fig. 5). On the driving shaft 29 there is a cam or irregular eccentric 151, engaging between 120 the fork arms of said lever 150.

Through the instrumentalities just described, the feed dog is given its backward and forward motion, with the proper dwells, at the ends of its travel. To give the feed dog its up and down motion, the lever 145 has at its forward end a pin and slot connection with a lever 152, which is clamped upon a rock shaft 154 journaled in bearings in the under side of the work support, 130

see Figs. 3 and 8. Secured to the rock shaft is another arm 155 (see Fig. 5), which is connected by a link 156 with a pin 157, projecting laterally from the bender-actuating lever 73, as shown in Figs. 1, 5 and 6. By reason of this construction, the up and down movement of the feed dog is controlled by the bender-actuating devices, whereas its forward and back movements are effected 10 directly from the main driving shaft. The feed dog traverses a four-way path, being depressed when the bender is depressed, and being raised into active position to feed the work when the bender is raised or moved 15 away from the work. Thus the movement of the feed dog up and down is coincident with the up and down movement of the bender.

Cooperating with the feed dog is the 20 presser foot 95, and it is of any convenient or desirable shape, having a foot portion 96, which is positioned at one side of the bender and immediately above the feed dog. The presser foot is attached to a lever 97, 25 the rear end of which is pivoted upon the shaft 74 previously referred to, and it is located on the projecting end of said shaft outside of the hump or projection 75, as best shown in Figs. 1 and 3. In plan view, 30 the lever 97 is deflected or crooked, extending forwardly, then to the left, and then slightly forwardly again, whereas in side elevation, as shown in Fig. 3, it is curved. Thus both the presser foot lever and the 35 bender-actuating lever are bent to the left, so as to extend laterally beyond the raised portion of the work support, and permit the work to pass freely by said raised portion as it is being fed.

40 The presser foot is held downward yieldingly while the machine is in operation, and for this purpose there is pivoted to the lever 97 a depending rod 98, which projects downwardly through the work support, and is provided on its lower threaded end with an adjusting nut 99.

Between the nut and the under side of the work support is a spring 100, which holds the presser foot downward yieldingly on 50 the face of the work. The lower end of the rod 99 is immediately above the arm 70 of the bell crank, which, as previously described, is connected to the rod 62, which is shifted when the treadle is depressed or released. When the treadle is released, so as to permit the spring 69 to move the stop pin into engagement with the stop cam and to swing the belt shifter so as to shift the belt to the loose pulley, the bell crank is 55 rocked about its axis, and the arm 70 thereof engages the depending rod 98, and raises the presser foot. When the treadle is depressed to set the machine in operation, the horizontal arm of the bell crank is depressed 60 to release the presser foot, and permit the

spring 100 to force it down yieldingly upon the face of the work.

In order that the needle bar, needle and take-up may be rendered readily accessible for threading, I have formed the work support with an elongated and relatively wide slot, extending from front to rear above these parts, as indicated at 158. This slot is normally closed by a cover plate 159, which extends rearwardly from the throat plate 86 to the rear wall of the work support. This cover plate is attached to a vertical pin 162, which is adapted both to slide and to rotate in a lug 160, projecting rearwardly from the rear wall of the work support. 70 75 80

A spring 161 encircles the pin, and has one end attached thereto, and the other end to the lug, so that, by placing the finger below the pin and pressing it upwardly, the 35 plate will be raised above the plane of the surface of the work support, and the spring will swing it laterally automatically, so as to uncover the slot in the work support. The spring serves two functions. When the 90 cover plate is in its normal position closing the slot, the spring tends to hold it in place; whereas, when the pin 162 is raised, the spring swings the cover plate to the side. In front of the throat plate 86 there is a 95 semicircular cover plate 163, which normally closes an aperture in the work support, and covers the shuttle and shuttle race. This last mentioned cover plate is provided with an ear 164, which is affixed to a pintle 165, journaled in the work support, and having an arm 166, as shown in Fig. 6. A spring 167 connects the arm with a pin 168 extending laterally into the work support from the inner side of the forwardly projecting part thereof. The purpose of this spring is to hold the cover plate normally closed. The ear 164 is provided with an extension 169, which may be engaged by a pin or projection 170 extending upwardly from 100 the top of the cover plate 28 for the bobbin receptacle, so that, when the cover plate 28 is swung upwardly, the pin or projection 170 will engage the extension 169, and raise the plate 163. The extension 169 is notched 110 115 so that, when the plate 28 is vertical, it will lock the cover plate 163 in its raised position.

I have constructed the means for holding the thread cones so that cones of different 120 lengths and sizes may be used on the machine. Referring to Fig. 15, 171 represents a rod projecting upwardly from the right end of the work support and having on its upper end a head 172, formed with a disk 125 173 having a frusto-conical or tapering flange 174. Secured in the disk is a sleeve 175, having an open end into which is passed a spindle 176. The spindle 176 is slotted near its end to provide two spring 130

members 177, 177 to yieldingly engage the interior walls of the sleeve 175, and frictionally hold the spindle therein. The spindle is provided with a head 178 and with a frusto-conical boss 179 of the same size as that shown at 174. Cones having a small internal diameter may be placed directly upon the sleeve 175, whereas cones having a larger internal diameter may be supported on the 5 conical or tapering bosses or flanges 174, 179.

10 On the throat plate is arranged a suitable device 200, of well known construction, for gathering the thrum ends and the stay cord in line, as indicated in Fig. 3, but any other 15 usual device for this purpose may be employed.

It is unnecessary to describe the operation 20 of the machine in detail, as the operation of the various instrumentalities has been described in the foregoing specification. It will be noted that the operating instrumentalities are all positively actuated, the connection between the said instrumentalities and the main driving shaft being such as 25 to insure rapidity of operation and smoothness of motion. I have dispensed with the employment of spring-pressed cam-actuated levers, and have utilized positive driving connections. Wherever springs are used in 30 the machine, they are not subjected to continuous compression and expansion due to the application of power thereto, being used only for operating the stop motion and belt-shifting devices, or for swinging the main 35 cover plate of the work support.

35 I shall not attempt to explain further the advantages which follow from the construction which I have illustrated and described, as they will be apparent to any one who 40 is familiar with the art to which this invention relates. I do desire, however, to point out that the invention is not limited to the details of construction which I have seen fit to employ, since the invention is capable 45 of a variety of other embodiments.

45 It will be understood that the drawings are more or less conventional, and that the language which I have employed is for the purpose of description rather than of limitation.

50 I also desire to have it understood that the use of the machine is not limited to the finishing of buttonholes of shoes and gaiters, although it is well adapted for that purpose, 55 since the machine and especially certain features of it, may be employed with advantage for blind-stitching various kinds of work, on account of the high speed at which it may be operated, and also on account of 60 its relative simplicity and durability.

60 Furthermore, while in order to set forth clearly the entire invention herein claimed, I have described certain novel mechanisms for actuating the needle and for driving and 65 stopping the machine, such mechanisms per-

se are not claimed herein, although parts thereof broadly defined are included as elements in certain combinations covered by this application. The novel features of said mechanisms, however, are the subject of two 70 co-pending and continuing applications, Serial No. 612,844 filed March 7, 1911, and Serial No. 618,348 filed April 1, 1911.

Having thus particularly described my invention, what I claim as new and desire to 75 secure by Letters Patent, is:—

1. A blind stitch sewing machine including in combination, a substantially flat work support having a hollow raised projection, a driving shaft mounted in bearings beneath 80 the work support, stitch-forming mechanism located and operating beneath the work support, a bender, and a bender carrier extending from the interior of said projection to a point above the work support, and also 85 extending beneath the work support and having means for connection to the driving shaft, whereby the same is actuated by said driving shaft.

2. A blind stitch sewing machine including in combination, a hollow casing having a base and a work support located above and spaced from said base, a driving shaft, devices for operating said driving shaft, a stop mechanism, said driving shaft, operating devices and stop mechanism being located between the work support and said base and within said hollow casing, stitch-forming mechanism, including a needle, located beneath the work support and actuated from said driving shaft, feeding mechanism located beneath the work support and actuated from said driving shaft, a presser foot above said work support and cooperating with said feeding mechanism, a bender located above said work support for bending the material into the path of the needle, and means for operating said bender. 95

3. A blind stitch sewing machine including in combination, a base, a work support 100 located above and spaced from said base, a driving shaft, a fast pulley carried by said driving shaft, a loose pulley adjacent said fast pulley, a belt shifter, and stop mechanism, said driving shaft, fast pulley, loose 105 pulley, belt shifter and stop mechanism being located between the work support and said base, stitch-forming mechanism, including a needle, located beneath the work support and actuated from said driving shaft, 110 feeding mechanism located beneath the work support and actuated from said driving shaft, a presser foot above said work support cooperating with said feeding mechanism, a bender located above said work support for bending the material into the path of the needle, 115 and means for operating said bender.

4. A blind stitch sewing machine including in combination, a base, a work support located above and spaced from said base, a driving shaft, a fast pulley carried by said driving shaft, a loose pulley adjacent said fast pulley, a belt shifter, and stop mechanism, said driving shaft, fast pulley, loose 120 pulley, belt shifter and stop mechanism being located between the work support and said base, stitch-forming mechanism, including a needle, located beneath the work support and actuated from said driving shaft, feeding mechanism located beneath the work support and actuated from said driving shaft, a presser foot above said work support cooperating with said feeding mechanism, a bender located above said work support for bending the material into the path of the needle and a bender carrier extending beneath the work support and operated by said driving shaft. 125

4. A blind stitch sewing machine includ- 130

- ing in combination, a base, a work support spaced from said base, and hinged thereto, a driving shaft mounted in bearings carried by the work support, a fast pulley mounted on said driving shaft, a loose pulley carried by said base, a belt shifter carried by said base, stitch-forming mechanism mounted beneath the work support and actuated by said driving shaft, feeding mechanism located beneath the work support and actuated from said driving shaft, a bender located above the work support, a bender carrier extending beneath the work support and actuated from said driving shaft, and means for locking the belt shifter with the belt held on the loose pulley while said work support is swung about its hinge and the fast pulley moved from its position adjacent the loose pulley.
- 29 5. A buttonhole finishing machine including, in combination, a work support, work feeding mechanism, stitch-forming mechanism including a needle located and operating beneath the work support, a driving shaft also located beneath the work support and extending transversely to the line of feed and to the path of the needle, a crank adjacent to one end of said shaft and connections therefrom to the needle, a bender carrier fulcrumed adjacent to and extending through the work support, a bender adjustably fixed to said carrier and an actuating device on said driving shaft co-operating directly with said bender carrier to force the material positively into the path of the needle.
- 40 6. A blind stitch sewing machine including, in combination, a work support, work feeding mechanism, stitch-forming mechanism located and operating beneath the work support, a driving shaft also located beneath the work support and extending transversely to the line of feed, a bender, a bender carrier, a fulcrum for said carrier located adjacent to the work support and extending at right angles to the line of feed, and an actuating device on said driving shaft, said carrier having an arm projecting above said fulcrum and connected to said bender and an arm projecting below said fulcrum and co-operating directly with said actuating device.
- 45 7. A buttonhole finishing machine including, in combination, a work support, a needle operating on one side of said work support, a bender, a bender carrier, mechanism acting positively upon the carrier to cause the bender to force the material into the path of the needle and means engaging the convex surface of the bent material and co-operating with the bender to hold said material bent during the passage of the needle therethrough, means for adjusting the bender on its carrier into such relation with the needle and with said engaging means that the nee-
- dle will pass through one thickness only of the material.
8. A buttonhole finishing machine including, in combination, a work support, a needle operating on one side of said work support, a bender, a bender carrier, mechanism acting positively upon the carrier to cause the bender to force the material into the path of the needle and means engaging the convex surface of the bent material and co-operating with the bender to hold said material bent during the passage of the needle therethrough, means for adjusting the bender on its carrier and means for clamping the bender in adjusted position.
- 15 9. A sewing machine including in combination, a work support, a needle operating at one side of said work support, a bender, a bracket carried by the work support at one side of said needle, pivoted arms supported by said bracket, said arms being laterally deflected, and jaws carried by said arms and co-operating with said bender.
- 25 10. A sewing machine including in combination, a work support, a needle operating at one side of said work support, a bender, a bracket carried by the work support at one side of said needle, pivoted arms supported by said bracket, said arms being laterally deflected, jaws carried by said arms and co-operating with said bender, a spring for forcing said jaws toward each other, and an adjustable tapered screw carried by said bracket and disposed between said arms for adjusting the distance between said jaws.
- 35 11. A sewing machine including in combination, a work support having a slot formed therein, a needle operating at one side of said work support, a bender, means for intermittently operating said bender to bend the material through the slot in the work support into the path of the needle, and receiving jaws located wholly below the work supporting surface of the work support and pressed yieldingly toward each other for holding said bent material during the entrance of the needle.
- 45 12. A sewing machine including in combination, a work support, a feeding mechanism, a needle operating beneath the work support in a direction substantially parallel with the line of feed, a bender for bending the material into the path of the needle, and relatively movable work receiving jaws located beneath the work support and clamping said material between themselves and the bender during the entrance of the needle.
- 55 13. A blind stitch sewing machine including, in combination, a work support, a needle operating beneath the work support, a bender, means for intermittently operating said bender to bend the material into the path of the needle, and a pair of relatively movable work-receiving jaws co-operating with the bender to hold the material bent.

- 5 during the entrance of the needle, said jaws being located wholly below the work supporting surface of the work support, means tending to move said jaws yieldingly toward each other and means for limiting such movement.
- 10 14. A blind stitch sewing machine including, in combination, a work support, work feeding mechanism, a needle operating beneath the work support in a direction substantially parallel with the line of feed, a bender for bending the material into the path of the needle, a bender carrier fulcrumed on an axis extending at right angles to the line of feed and being located above the work support on that side of the operating point toward which the work is fed, and means coöperating with the bender to hold the material bent during the entrance of the needle, said means presenting an opening 15 for the material which extends downward and in the direction of the feed.
- 15 15. A blind stitch sewing machine including in combination, a work support, a needle operating on one side of said work support, means for bending the material into the path of the needle comprising a bender, a support therefor, means for positively vibrating said support in predetermined time relation to the movement of the needle, 20 means for positively adjusting the bender on its support, and means for securing the bender in adjusted position.
- 25 16. A sewing machine including in combination, a work support, a needle operating on one side of said work support, a bender, an arm on which said bender is mounted, a screw for adjusting the position of the bender on said arm, and a clamp for fastening said bender in adjusted position.
- 30 17. A blind stitch sewing machine for finishing buttonholes comprising, in combination, a work support, work feeding mechanism, stitch-forming mechanism, including a needle, located and operating beneath the work support and covered thereby, a driving shaft also located beneath the work support and extending transversely to the line of feed and the path of movement of the needle, means for actuating said needle from said shaft, a bender, a curved, rigid bender lever fulcrumed adjacent to the work support and extending both above and below the work support, the bender being rigidly 35 but adjustably secured to said lever at its upper end, and a cam on the driving shaft directly engaging the lower arm of the bender lever and actuating the bender positively to bend the material into and hold it in the path of the needle so that the needle will pass through one thickness only of the material.
- 40 18. A sewing machine including in combination, a work support, a needle operating on one side of said work support, a bender, a 45 pivoted lever having said bender connected to its free end, staggered forked arms on the other end of said lever, a shaft and a double eccentric on said shaft having members for respectively engaging said forked arms and imparting positive movements to said lever.
- 50 19. In a blind stitch sewing machine, the combination with a double eccentric 85 of a bender 72 and a pivoted bender lever 73 at one end of which the bender is rigidly secured while the other end is provided with staggered forked arms 81, 82; constructed and operating substantially as described.
- 55 20. A sewing machine including in combination, a work support, work feeding mechanism, a needle operating beneath the said work support, a bender above the work support, a pivoted lever connected at its free end to said bender and extending at its other end beneath the work support, a fulcrum for said lever above the work support extending at right angles to the line of feed, a shaft beneath the work support, and means carried by said shaft for directly engaging and positively operating said lever.
- 60 21. A sewing machine including in combination, a work support, a needle operating beneath the work support, a bender, a pivoted lever rigidly connected at its free end above the work support to said bender, the other end of said lever extending beneath the work support, a shaft beneath the work support, an eccentric member carried by said shaft, said lever having a fork coöperating with said eccentric member.
- 65 22. A sewing machine including in combination, a work support, having a hollow slotted projection on its upper face, a needle operating beneath the work support, a bender, a lever extending from said hollow slotted projection, means for connecting one end of said lever to said bender, a shaft beneath the work support, and means carried by said shaft for engaging and operating the other end of said lever.
- 70 23. A sewing machine including in combination, a work support having a hollow slotted projection on its upper face, a needle operating beneath the work support, a bender, a lever extending from said hollow slotted projection, a pivotal support for said lever attached to the walls of said projection, a shaft beneath the work support, and means carried by said shaft for engaging and operating said lever.
- 75 24. A sewing machine including in combination, a work support, a needle operating beneath the work support, a bender for bending the material into the path of the needle, a hollow slotted projection formed in said work support on the upper face thereof in the rear of the bender, a lever extending from said hollow slotted projection, a pivotal support for said lever attached to the walls of said projection, a shaft beneath the

work support, and means carried by said shaft for engaging and operating said lever.

25. A sewing machine including in combination, a work support, a needle operating beneath the work support, a feeding mechanism, a bender for bending the material into the path of the needle, a lever fulcrumed in the rear of said bender and at one side of the line of feed and movable substantially in a plane parallel to the line of feed, the free end of said lever being laterally deflected and connected to said bender, and means for operating said lever.

26. A sewing machine including in combination, a work support, a needle operating beneath the work support, a feeding mechanism, a bender for bending the material into the path of the needle, a lever fulcrumed in the rear of said bender and at one side of the line of feed and movable substantially in a plane parallel to the line of feed, the free end of said lever being laterally deflected and connected to said bender, and the other end of said lever extending beneath the work support, a shaft beneath the work support, and means carried by said shaft for engaging and operating said lever.

27. A sewing machine including in combination, a work support, a needle operating beneath the work support, a feeding mechanism, a bender for bending the material into the path of the needle, a hollow slotted projection formed in said work support on the upper face thereof in the rear of the bender, and at one side of the line of feed, a lever fulcrumed in said hollow projection and extending therefrom, said lever being laterally deflected and connected to said bender at its free end, and the other end of said lever extending beneath the work support, a shaft beneath the work support, and means carried by said shaft for engaging and operating said lever.

28. A sewing machine including in combination, a work support, a needle operating beneath the work support, a feeding mechanism, a bender for bending the material into the path of the needle, a hollow slotted projection formed in said work support on the upper face thereof in the rear of the bender and at one side of the line of feed, a lever fulcrumed in said hollow projection and extending therefrom, said lever being laterally deflected and connected to said bender at its free end, the other end of said lever extending beneath the work support, a shaft beneath the work support, means carried by said shaft for operating said lever, a presser foot co-operating with the feeding mechanism, an arm pivotally supported by said hollow slotted projection, said arm being laterally deflected, and means for connecting said arm to the presser foot.

29. A blind stitch sewing machine includ-

ing, in combination, a work support, a driving shaft, a needle operating beneath the work support, a feed bar, a feed dog carried thereby, means for reciprocating the feed bar bodily back and forth in a single plane, a bender, connections between said shaft and said bender for operating the latter to bend the material being operated upon into the path of the needle, and mechanism for raising and lowering the feed bar and dog joined to said connections at a point thereof intermediate the shaft and the bender.

30. A blind stitch sewing machine including, in combination, a work support, a driving shaft, a needle and needle bar operating beneath the work support, a bender, means for operating the bender to bend the material being operated upon into the path of the needle, a feed dog mounted independently of said bender, means for reciprocating the feed dog in a single plane located at an angle to the surface of the work support and mechanism connected to said driving shaft for raising and lowering said feed dog, part of said mechanism being common to and part being separate from the bender operating mechanism.

31. A blind stitch sewing machine including, in combination, a work support, a driving shaft, a needle reciprocating beneath the work support, a feed dog movable in a single vertical plane parallel to the line of reciprocation of the needle, means for reciprocating the feed dog, a pivoted bender oscillating substantially in a plane parallel to the line of feed, and connections between said driving shaft and said bender for operating the latter to bend the material being operated upon into the path of the needle, and mechanism for raising and lowering the feed dog joined to said connections at a point thereof intermediate the shaft and the bender.

32. A blind stitch sewing machine including, in combination, a work support, a driving shaft extending transversely to the line of feed, a needle operating beneath the work support, a bender, connections between said shaft and said bender for operating the latter to bend the material being operated upon into the path of the needle, a feed dog, a feed bar to which the dog is secured and which is movable in a single vertical plane, connections from said shaft to said bar for positively reciprocating the feed bar longitudinally back and forth in said plane and connections from the bender operating mechanism to said feed bar for raising and lowering the feed dog simultaneously with the bender.

33. A blind stitch sewing machine including, in combination, a work support, work feeding mechanism including a feed bar, a feed dog carried thereby, a presser foot co-operating with said dog, means for positively

- reciprocating the feed bar longitudinally back and forth in a single plane, a needle operating beneath the work support and in a line parallel with the line of feed, a bender, a pivoted bender lever, means for raising and lowering the bender lever, and means connected to said bender lever between its ends for simultaneously raising and lowering said feed bar.
34. A sewing machine including in combination, a work support, a needle operating beneath the work support, a feed dog, means for operating said feed dog, a presser foot coöperating with said feed dog, a bender located at one side of said feed dog and presser foot, and independent thereof, and relatively movable jaws beneath the work support located at one side of said feed dog and coöperating with said bender to receive and hold the material for the needle.
35. A sewing machine including in combination, a work support, a needle operating beneath the work support and parallel with the line of feed, a feed dog, means for reciprocating said feed dog, a presser foot coöperating with said feed dog, a bender extending at right angles to the line of feed and independent of and located at one side of said presser foot for bending the material into the path of the needle, movable receiving jaws located beneath the work support at one side of said feed dog and coöperating with said bender to receive and hold the material for the needle, and means for simultaneously raising and lowering the bender and the feed dog.
36. A sewing machine including in combination, a work support, a driving shaft beneath the work support, a bender, means for reciprocating said bender from said driving shaft, a feeding mechanism, a needle bar located beneath the work support and reciprocating in a direction parallel with the line of feed, a needle carried by said needle bar, a crank arm at the end of the driving shaft, a link connecting said crank arm to the needle bar, a shuttle coöperating with said needle, a second crank arm at the forward end of said driving shaft, and a second link connected to said second crank arm for operating said shuttle.
37. A sewing machine including in combination, a work support, a driving shaft beneath the work support, a feeding mechanism, a needle bar located beneath the work support and reciprocating parallel with the line of feed, a needle carried by said needle bar, a crank arm at the forward end of the driving shaft, a link connecting said crank arm to said needle bar, a shuttle coöperating with said needle, a second crank arm at the forward end of said driving shaft, a link connected with said second crank arm for operating said shuttle,
- bender for bending the material into the path of the needle, an eccentric member adjacent the forward end of said driving shaft, a lever for operating said bender, and having a forked end coöperating with the eccentric member on the driving shaft.
38. A sewing machine including in combination, a work support, a driving shaft beneath the work support, a feeding mechanism, a needle bar located beneath the work support and reciprocating parallel with the line of feed, a needle carried by said needle bar, a crank arm at the forward end of the driving shaft, a link connecting said crank arm to said needle bar, a shuttle coöperating with said needle, a second crank arm at the forward end of said driving shaft, a link connected with said second crank arm for operating said shuttle, a bender for bending the material into the path of the needle, an eccentric member adjacent the forward end of said driving shaft, a lever for operating said bender and having a forked end coöperating with the eccentric member on the driving shaft; a second shaft operated by said driving shaft, and means operated from said second shaft for vibrating said needle laterally.
39. A blind stitch sewing machine comprising, in combination, a work support, work feeding mechanism, stitch-forming mechanism located and operating beneath the work support and including a reciprocating needle and a shuttle movable about a vertical axis and coöperating with the needle, a driving shaft also located beneath the work support and extending transversely to the line of feed, a bender, a rigid bender lever fulcrumed adjacent to the work support and extending both above and below the work support, means for rigidly but adjustably securing the bender to the upper arm of the lever, a cam on the driving shaft directly coöperating with the lower arm of the lever and actuating the bender positively to bend the material into the path of the needle, and connections from said driving shaft to said shuttle and needle respectively to actuate them positively in a predetermined timing relatively to the movements of each other and the bender, said connections including a crank adjacent to the end of the driving shaft by which the needle is reciprocated.
40. A blind stitch sewing machine comprising, in combination, a work support, work feeding mechanism, stitch-forming mechanism including a needle reciprocating beneath the work support in a line parallel to the line of feed and a shuttle oscillating about a vertical axis and coöperating with the needle, mechanism for vibrating the needle transversely to the line of feed between successive complete reciprocations of the

needle, a driving shaft also located beneath the work support, a bender, a bender lever fulcrumed adjacent to and extending through the work support, to which lever the bender is rigidly but adjustably secured and direct connections from said driving shaft to said shuttle and needle respectively to oscillate the shuttle and reciprocate the needle in predetermined timing relatively 10 to the movements of each other and the bender.

41. A blind stitch sewing machine including, in combination, a work support, a needle operating on one side of the work support, a 15 rotary shuttle co-operating therewith, a driving shaft located beneath the work support, a bender, means for operating said bender to bend the material into the path of the needle, a double crank upon said shaft having 20 its two crank pins located at opposite sides of the shaft and separate operating connections from said crank pins to said needle and shuttle respectively.

42. A blind stitch sewing machine including, in combination, a work support, feeding mechanism, a driving shaft beneath the work support and extending transversely to the line of feed, a bender, means for reciprocating said bender from the driving 25 shaft, a needle located beneath and covered by the work support and reciprocating in a line parallel to the line of feed, a shuttle co-operating with the needle, a double crank at the end of said shaft having its two crank 30 pins located on opposite sides of the shaft and separate operating connections from said crank pins to said needle and shuttle respectively, the arrangement of the crank pins being such that the momentum of the 35 moving parts connected to one of the pins substantially counterbalances the momentum of the moving parts connected to the other pin so that vibration is reduced to a minimum.

43. A sewing machine including, in combination, a needle, a horizontally reciprocating needle bar, a shuttle co-operating therewith, a driving shaft, a crank arm on the end of said shaft, a second crank arm carried by the same end of the shaft and extending to the opposite side of the axis of the shaft from the first-named crank arm, and separate operating connections between the needle bar and the shuttle and the 45 respective crank arms to reciprocate the bar and actuate the shuttle, the operating connections being moved simultaneously in opposite directions to equalize strains and overcome vibration due to momentum of the 50 moving parts.

44. A sewing machine including, in combination, a needle, a reciprocating needle bar and a rotary shuttle co-operating therewith, a driving shaft, a crank arm on the

end of said shaft, a second crank arm rigidly connected to said first-named arm by a crank pin, a second crank pin on said second-named arm, the two crank pins being disposed on opposite sides of the axis of the shaft, and separate operating connections between the needle bar and the shuttle and the respective crank arms to reciprocate the bar and oscillate the shuttle, the operating connections being moved simultaneously in opposite directions to equalize strains and overcome vibration due to momentum of the moving parts.

45. A sewing machine including in combination, a work support, feeding mechanism, a needle bar, a needle carried thereby and operating beneath the work support, means for reciprocating said needle bar in a line substantially parallel with the work support and the line of feed, complementary stitch-forming mechanism, means for bending the material into the path of the needle, and a take-up for the needle thread located and operating wholly beneath the work support and in a plane adjacent the needle path.

46. A sewing machine including, in combination, a work support, feeding mechanism, a needle and a needle bar reciprocating in the line of feed beneath the work support and covered thereby, complementary stitch-forming mechanism, means for bending the material into the path of the needle, a pivoted take-up arm located wholly beneath the work support and having a thread eye at its outer end and means for moving said take-up arm to cause said thread eye to move positively to and fro in a path substantially parallel with and adjacent to the path of the needle.

47. A sewing machine including, in combination, a work support, feeding mechanism, a driving shaft extending transversely to the line of feed, a needle bar wholly beneath the work support, a needle carried thereby, connections from said driving shaft for reciprocating said needle bar in a line substantially parallel with the work support and the line of feed, means for bending the material into the path of the needle, a take-up located and operating wholly beneath the work support and in a plane adjacent to the needle path and connections from said driving shaft but independent of said needle bar for positively actuating the take-up in opposite directions.

48. A sewing machine including, in combination, a work support, feeding mechanism, a driving shaft extending transversely to the line of feed, a needle bar wholly beneath the work support, a needle carried thereby, means for bending the material into the path of the needle, a pivoted take-up arm having a thread eye, said arm being located wholly beneath the work support

and mounted on a fixed fulcrum, and connections from one end of said driving shaft to said needle bar and take-up respectively for moving the needle and the thread eye in paths which are adjacent to but beneath the work support and substantially parallel to each other and to the line of feed.

49. A sewing machine including in combination, a work support, feeding mechanism, a needle bar located beneath the work support and reciprocating in a line parallel to the line of feed, an arm supported by said needle bar with its free end adjacent the under face of the work support, a needle carried by said arm, complementary stitch-forming mechanism, means for bending the material into the path of the needle, and a take-up arm pivoted beneath the work support and having its free end swinging in a path adjacent a line containing the path of the needle.

50. A sewing machine including in combination, a work support, feeding mechanism, a needle bar located beneath the work support and reciprocating in a line parallel to the line of feed, an arm supported by said needle bar with its free end adjacent the under face of the work support, a needle carried by said arm, complementary stitch-forming mechanism, means for bending the material into the path of the needle, a take-up arm pivoted beneath the work support and having its free end swinging in a path adjacent a line containing the path of the needle, a main shaft beneath the work support, a crank arm carried by the main shaft and having a link connection with the needle bar, and a second crank arm carried by said shaft and at an angle to the first named crank arm and having a link connection with the take-up arm.

51. A sewing machine including in combination, a work support, a driving shaft beneath the work support, a bender, means for positively reciprocating said bender from said driving shaft, a feeding mechanism, a needle bar located beneath the work support and reciprocating in a direction parallel with the line of feed, a needle carried thereby, a crank arm at the end of the driving shaft, a link connecting said crank arm to the needle bar, a shuttle coöperating with said needle, a second crank at the forward end of said driving shaft, a second link connected to said second crank for operating said shuttle, a take-up arm located beneath the work support, a third crank arm carried at the forward end of said driving shaft, and a third link connected to said third crank arm for operating said take-up arm.

52. A sewing machine including in combination, a work support, a driving shaft beneath the work support, a feeding mecha-

nism, a needle bar located beneath the work support and reciprocating parallel to the line of feed, a needle carried by said needle bar, a crank arm at the forward end of the driving shaft, a link connecting said crank arm to said needle bar, a shuttle coöperating with said needle, a second crank arm at the forward end of said driving shaft, a link connected with said second crank arm for operating said shuttle, a bender for bending the material into the path of the needle, a take-up arm located beneath the work support, a third crank arm carried at the forward end of said driving shaft, a link connected to said third crank arm for operating said take-up arm, an eccentric member adjacent the forward end of said driving shaft, a lever for operating said bender and having a forked end coöperating with the eccentric member on the driving shaft.

53. A sewing machine including in combination, a work support, a driving shaft beneath the work support, a feeding mechanism, a needle bar located beneath the work support and reciprocating parallel with the line of feed, a needle carried by said needle bar, a crank arm at the forward end of the driving shaft, a link connecting said crank arm to said needle bar, a shuttle coöperating with said needle, a second crank arm at the forward end of said driving shaft, a link connected with said second crank arm for operating said shuttle, a take-up arm located beneath the work support, a third crank arm carried at the forward end of said driving shaft, a link connected to said third crank arm for operating said take-up arm, a bender for bending the material in the path of the needle, an eccentric member adjacent the forward end of said driving shaft, a lever for operating said bender and having a forked end coöperating with the eccentric member on the driving shaft, a second shaft operated by said driving shaft, and means operated from said second shaft for vibrating said needle laterally.

54. A sewing machine including in combination, a work support, a needle operating beneath the work support, a feeding mechanism, a bender for bending the material into the path of the needle, a lever fulcrumed in rear of said bender and at one side of the line of feed on which said bender is mounted, a presser foot engaging the material adjacent the bender, a supporting lever therefor, said lever being fulcrumed in the rear of said bender and at one side of the line of feed.

55. A sewing machine including in combination, a work support, a needle operating beneath the work support, a feeding mechanism, a bender for bending the material into the path of the needle, a lever fulcrumed in rear of said bender and at one side of the

line of feed on which said bender is mounted, a presser foot engaging the material adjacent the bender, a supporting lever therefor, said lever being fulcrumed in the rear of said bender and at one side of the line of feed, the fulcrum for said presser foot lever being in line with the fulcrum for the bender lever.

56. A sewing machine including in combination, a work support, a needle operating beneath the work support, a feeding mechanism, a bender for bending the material into the path of the needle, a hollow slotted projection carried by said work support in the rear of the bender and at one side of the line of feed, a lever fulcrumed in said hollow projection and extending therefrom, said lever being laterally deflected and connected to said bender at its free end, a shaft beneath the work support, the other end of said lever extending beneath the work support, means carried by said shaft for engaging and operating said lever, a presser foot located adjacent said bender, and a lever carrying said presser foot, said lever being laterally deflected and pivotally supported on the outer face of said slotted projection.

57. A sewing machine including in combination, a work support, a needle operating beneath the work support, a feeding mechanism, a bender for bending the material into the path of the needle, a hollow slotted projection carried by said work support in the rear of the bender and at one side of the line of feed, a lever fulcrumed in said hollow projection and extending therefrom, said lever being laterally deflected and connected to said bender at its free end, a shaft beneath the work support, the other end of said lever extending beneath the work support, means carried by said shaft for engaging and operating said lever, a presser foot located adjacent said bender, and a lever carrying said presser foot, said lever being laterally deflected and pivotally supported on the outer face of said slotted projection, the pivotal axis of the presser foot supporting lever being in line with the pivotal axis 50 of the bender supporting lever.

58. A sewing machine including in combination, a work support, a needle operating beneath the work support, a feed dog, means for operating said feed dog, a presser foot coöoperating with said feed dog, a bender located at one side of said presser foot for bending the material into the path of the needle, and receiving jaws located at one side of said feed dog and coöoperating with said bender, a lever fulcrumed in rear of said bender and at one side of the line of feed, for supporting said bender, and a second

lever fulcrumed in rear of said bender and at one side of the line of feed for supporting said presser foot.

65

59. A buttonhole finishing machine including, in combination, a work support, a needle operating beneath the work support, feeding mechanism, a bender for bending the material into the path of the needle, a lever on which the bender is mounted and which is fulcrumed adjacent to the work support and at one side of the line of feed, a presser foot engaging the material adjacent to the bender and a supporting lever therefor fulcrumed co-axially with the bender lever.

60. A buttonhole finishing machine including, in combination, a work support, a driving shaft beneath the work support, a needle also beneath the work support, feeding mechanism, a bender for bending the material into the path of the needle, a lever on which the bender is mounted, which is fulcrumed adjacent to the work support and at one side of the line of feed and which extends through the work support, an actuating device on said shaft and coöperating directly with the bender lever, a presser foot engaging the material adjacent to the bender and a supporting lever therefor fulcrumed co-axially with the bender lever.

61. A buttonhole finishing machine including, in combination, a work support, work feeding mechanism operating in a plane at an angle to the surface of the work support, stitch-forming mechanism including a needle reciprocating beneath the work support in a line substantially parallel to the line of feed and a shuttle moving about a vertical axis and coöperating with the needle, a driving shaft also located beneath the work support and extending transversely to the line of feed and to the path of the needle, a crank at one end of said shaft and connections therefrom for reciprocating the needle, mechanisms actuated from said shaft for actuating the shuttle and for vibrating the needle transversely to the line of feed between successive complete reciprocations of the needle, a lever fulcrumed between its ends and adjacent to the work support, a bender carried at one end of the lever, a cam on the driving shaft for actuating the bender to bend the material into the path of the needle and means by which the relative positions of bender and cam may be manually adjusted.

In testimony whereof I have affixed my signature, in presence of two witnesses.

GEORGE S. HILL.
